UNITED STATES PATENT OFFICE

162,167

TRIM BAR FOR AUTOMOBILE FENDERS OR THE LIKE

Leonard A. Hunting, Independence, Mo., and
Lee M. Goldstine, Chicago, Ill.

Application January 26, 1950, Serial No. 7,482

Term of patent 14 years

(CL. D14—6)

To all whom it may concern:

Be it known that we, Leonard A. Hunting and Lee M. Goldstine, citizens of the United States and residents of Independence, Missouri, and Chicago, Illinois, respectively, have invented a new, original, and ornamental Design for a Trim Bar for Automobile Fenders or the Like, of which the following is a specification, reference being had to the accompanying drawing, forming a part thereof.

Fig. 1 is a front elevational view of a trim bar for automobile fenders or the like, showing our new design.

Fig. 2 is a top plan view of the same.

Fig. 3 is a right end elevational view of the same.

Fig. 4 is a left end elevational view of the same.

We claim:

The ornamental design for a trim bar for automobile fenders or the like, substantially as shown.

LEONARD A. HUNTING.

LEE M. GOLDSTINE.
